(57) CLAIM

The ornamental design for a display screen or portion thereof with graphical user interface for sports streaming portal, as shown and described.

DESCRIPTION

The FIGURE is a front view of a display screen or portion thereof with graphical user interface for sports streaming portal.

The outer broken lines illustrate a display screen or portion thereof and the remaining broken lines illustrate portions of the graphical user interface for a sports streaming portal. None of the broken lines form part of the claimed design.
